UNITED STATES PATENT OFFICE.

EDWARD W. POWERS, OF BOSTON, MASSACHUSETTS.

PIANO.

Application filed July 21, 1926. Serial No. 123,950.

This invention relates to stringed instruments and more particularly to pianos.

In the accompanying drawings, wherein I have shown merely for illustrative purposes 5 a complete embodiment of the invention:

Fig. 1 is a plan view of a stringed instrument of the grand piano type with the top, rack and keys omitted;

Fig. 2 is a detail vertical section taken on 10 the line 2—2 of Fig. 1;

Fig. 3 is a detail vertical section taken on the line 3—3 of Fig. 1;

Fig. 4 is a detail vertical section taken on the line 4—4 of Fig. 1;

Fig. 5 is a detail vertical section taken on 15 the line 5—5 of Fig. 1;

Fig. 6 is a plan view of the form of individual strut and its auxiliary bridge, herein used in the upper treble sections;

Fig. 7 is a detail side view of the individual 20 resilient string supporting struts shown in Fig. 6 with the adjacent portion of the bridge and sounding board shown in section;

Fig. 8 is a right hand end view of the strut 25 shown in Fig. 6;

Fig. 9 is a section taken on the line 9—9 of Fig. 5;

Fig. 10 is a side view of a modified form 30 of strut together with a cross-section of the associated bridge and a portion of the sounding board.

Fig. 11 is a detail plan of a modified form 35 of string plate and strut; and

Fig. 12 is a vertical section taken on the line 12—12 of Fig. 11.

Obviously the invention embodied herein is adaptable for use in connection with various forms of stringed instruments, but in the present exemplification I prefer to show the 40 same applied to a grand piano having a casting 1 wherein are mounted the various piano elements including a string plate 3, a piano action indicated briefly at 5, Fig. 2, and the usual sounding board 7 which herein is under 45 stress to exert pressure in a direction substantially perpendicular to said board. The string plate 3 is of substantially rigid construction embodying a head 9 for carrying the tuning pins 11, a bearing bar 13 and a lower plate member 15.

The head and lower plate members 9 and 15 respectively are separated by a substantial opening 17 which extends substantially across the string plate along the line of the 55 bridge and of a sufficient width to provide convenient access to the strings and their

supporting means and to the bridge or bridge elements located beneath the plate.

To provide sufficient rigidity between the two plate sections means are provided for 60 bridging said space or opening 17, said means including in part integral ribs or struts 19, said integral struts extending along the top of the web portion of the plate head 9 to unite the bearing bar 13 and lower margin 65 18 of the opening 17 with ribs 21 and 23 arranged transversely of said plate.

In addition to the integral struts 19 I provide separable reenforcing struts 25 which are inserted at certain sections between the 70 margin 18 and ribs 21 where considerable tension is exerted upon the plate by reason of the tightly drawn strings, and these struts are made separable so that they may be left out until after the springing of the plate 75 has taken place in order to provide ample working space for the connecting up or placing of strings and particularly the individual bridge elements.

The struts 19 and 25 are herein arranged 80 to lie parallel with the strings, and the struts 19, which as hereinbefore stated extend over the head portion of the plate, are designed to lie in suitable gaps provided between certain sets of strings so as not to interfere with 85 the activities of said strings, said integral struts or ribs being extremely thin as regards their transverse dimensions and substantially deep perpendicularly to the web of said string plate provide ample strength yet occupying but little transverse space.

The strings of the instrument are stretched across the string plate 3 desirably in the usual order as for example in a series 27 including upper, middle and lower treble 95 strings and a series 29 constituting bass strings.

The lower treble group herein designated 28 lies in a plane with the middle and upper treble strings of the group 27, while the bass 100 string group 29 extends diagonally across the treble group 28 and in a plane herein above said treble strings.

Ordinarily both the head and tail ends of the strings of the several groups are secured 105 directly to the rigid metallic string plate 3 with the result that vibrations of the strings are transmitted directly to the plate and in consequence said plate is caused to vibrate and produce harsh discordant metallic sounds 110 that tend materially to destroy or at least drown out the purer musical tones of the

instrument. To overcome these objections the tails of strings are herein resiliently mounted with respect to the string plate in a manner somewhat similar to that disclosed in my prior Patent No. 1,576,545 of March 16, 1926.

Desirably the means herein employed for resiliently supporting said strings are in substance cantilever struts having ends or bases rigidly fixed to some relatively rigid part of the instrument such as the string plate 3 between the ends of the strings, the tails of which strings are secured to the free ends of said struts and lie approximately parallel therewith so that each string will be supported substantially unyieldingly in a direction of its length but capable of lateral deflection without causing any material variations in the tension of the string.

It is also a feature of this invention to vary the proportion, shape or character of the various struts of the instrument in order to provide just the right degree of lateral resiliency or the stability required to oppose or counter-balance the pressure exerted by the adjacent portion of the sounding board upon each string.

In order that the last statement may be clearly understood it should be borne in mind that the bass strings are long and relatively massive, requiring a strut of maximum stiffness to withstand the string activity and also to withstand or balance a large portion of the entire pressure exerted by the sounding board upon the strings due to the arching of the board, although some of this pressure is borne by the lower treble strings which, in the usual piano construction, underlie and cross said bass strings. The remaining middle and upper treble strings are called upon to resist gradually diminishing degrees of sounding board pressure until at the upper end of the series where the activity of the strings is greatest very little, if any, board resistance will be encountered and consequently these strings will have a higher degree of freedom.

By reason of this arrangement it will be possible to maintain a condition of poise or a balance between the forces exerted by the strings under tension and the sounding board together with any additional pressure exerted by the bridge upon the sounding board, thus constituting a balance of forces that will be proportionate to the string mass and the velocity of vibration such as will promote increased harmonic activity throughout the scale of the instrument.

In carrying out this feature of the invention the cantilever struts or resilient supporting means designated generally as 30, although varying considerably in design, strength and character, according to location, have at least one common characteristic in that they are secured or fixed rigidly to the string plate or other relatively fixed part of the instrument between the ends of the strings

so that all deflection of said struts will be in a direction lateral to the strings and yet the supporting ability of the struts in a longitudinal direction will not be materially reduced nor the string tension varied during string activity.

In the present embodiment of my invention the struts for the treble strings or unisons are desirably individual in form, but owing to the necessarily close arrangement of the strings in the upper groups, say for example the groups 32 and 33 of Fig. 1, and to the fact that the struts for these strings have little board pressure to resist, they are of relatively small dimensions and formed with a cylindrical base or stem 31 shouldered at 32. The stem 31 fits an appropriate recess 33 formed in a rib 34 depending from a plate 35 which latter is secured by screws 36 to the under side 45 of the string plate 3. The shoulder 32 of the strut seats against one face of the rib 34 and receives the end thrust of said strut produced by the tension of the string or strings carried thereby.

In each of the groups above mentioned the struts 30 are fixed indirectly to the face 45 of the plate 3 across which face are stretched the strings composing groups 32, 33, and 36, although it is to be understood that the invention is not limited to this arrangement of securing the struts to the plate nor to the particular forms of struts shown.

In that section of the plate where the strings are longer and heavier, as for example in the lower treble group 28 and in the bass group 29, a more rigid and stiffer strut is desirably employed because, as hereinbefore stated, these strings are called upon to resist most of the sounding board pressure. Therefore the supporting means for the series of strings 28 is made in the form of an auxiliary plate 49, herein shown as extending the entire length of the group and secured by screws and dowels 51 and 53 to the edge 55 of the lower plate portion 15, said edge 55 lying between the ends 110 of the strings of said group 28 as hereinbefore mentioned. The tails of the strings of the groups 28 may be secured to the free outer edge of the auxiliary plate 49 by any appropriate means, but herein they are attached to 115 the usual hitch pin 57 secured in said auxiliary plate.

The bass strings 29 are provided with resilient supporting means for the tail ends thereof similar to the supporting means for the group 28, although these supporting means are materially heavier and less resili- 120 ent than the former for the reason that said bass strings are much longer and heavier than said strings 28. In this connection I 125 employ a second auxiliary plate 59 secured by screws and dowels 61 and 63 to the marginal portion 65 of the plate section 15. This secured edge of the second auxiliary plate 59 lies between the ends of the strings 29 and 130

substantially parallel with said strings, the tails of said strings being secured to the free edge 67 of said second auxiliary plate in any appropriate manner such for example as by 5 hitch pins 69.

The sounding board 7 is placed under stress by arching the same in the frame 1 in such a manner that the pressure exerted by said sounding board will be directed laterally to 10 the strings stretched across the plate 3.

The struts of the groups of strings 32, 33 and 36 are secured as previously stated to the under face 45 of the string plate across which the strings are strung and adjacent to which 15 face the sounding board 7 is also arranged, consequently the strings which are hitched to said struts will have a tendency to deflect said struts 30 away from the face 45 toward the sounding board 7, and with proper 20 portioning of said struts it will be apparent that the precise amount of resistance to the upward pressure of the sounding board 7 through connecting instrumentalities herein-after explained may be provided whereby the 25 pressure produced by the tension of said struts and the pressure of said sounding board will be nicely balanced, or, as herein-before stated, a condition of poise between the strings and the sounding board will be 30 maintained so as to promote increased harmonic activity through the scale.

The crossing of the strings of the group 28 with those of the group 29 require a somewhat different arrangement, particularly with regard to the resilient supports for the strings 28 which lie beneath the bass strings 29. Consequently in the present example the frame 3 has a depressed shelf 71 and the strut plate 49 is secured, herein by the screws 51, to the 35 upper face 73 of said shelf which lies above the sounding board 7 and between said board and the strings 28, although it is to be understood that the invention is not limited to the supporting of said strings above said plate. 40 This method of attaching the auxiliary plate 49 to the string plate produces an action due to the tension of the strings 28 tending to spring the plate 49 upwardly in the same direction in which the pressure exerted by the 45 sounding board 7 acts upon said strings, this being another reason for providing a stiffer strut for this group of strings than was necessary for the strings of the groups 32, 33 and 36. The auxiliary strut plate 59 for the bass strings is similarly secured, herein against the face 75 of the depressed shelf 77 of the frame 3. It is however to be understood that the invention is not limited to the relative arrangement of the strut plates and string 50 plate herein shown.

Any appropriate bridge means may be provided for operatively connecting the strings to the sounding board, but in the present example I have shown the strings of the groups 55 28 and 29 connected to wooden bridges 79

and 81 respectively by the usual inclined hitch pins 83 and the bridges 79 and 81 are desirably secured to the adjacent face of the sounding board 7 and under stress so as to add to the pressure of the sounding board laterally 70 upon said string. The bridges 79 and 81 are herein shown as extending approximately the length of their respective auxiliary struts.

It is within the scope and purpose of the invention to employ hitch pins similar to the 75 hitch pins 57 and 69 of the bass and lower treble strings for securing the upper treble strings to their individual struts and also to employ bridge means similar to those herein-before described, but desirably with struts 80 which are not called upon materially to assist in maintaining the board pressure and hence have greater freedom of activity, as in the case of the struts of said upper strings, bridge means are provided between the free ends of 85 said struts (see particularly Figs. 2, 3, 5, 6, 7 and 8) and the adjacent portions of said sounding board 7 which insure the movements of said free ends in unison with said sounding board. 90

To this end I provide means including a sounding board reenforcing strip 85 of wood or other appropriate material secured directly to the upper or crown face of said sounding board, and between it and the free end of each individual strut I provide an individual bridge 87, herein in the form of an angle, one leg of which is secured by a screw 89 to the reenforcing strip 85. The other leg of said angle is extended upwardly and fits into 100 a properly formed recess 91 in the under end portion of said strut, and the string supported by said strut is interlaced through the up-standing leg of said angle 87 and the end of said strut in such a manner that when tension is applied to the string in tuning the engaging portions of the strut and angle will be 105 firmly and positively bound together so as to prevent all rattle between the engaging surfaces even under excessive vibration of the 110 string.

Each strut 30 may support one, two or more strings but ordinarily strings are arranged in groups of three called unisons and this practice is desirably followed in the 115 present example. In following out this arrangement the end of the middle string 93 of the unison is passed through an eye 95 arranged centrally of the upstanding arm of the angle 87 and bent over the end of the 120 strut 30, thence passing downwardly into a hole 97 in the upper face of said strut, the opposite end of the middle string passing along the face of the plate to one of the tuning pins 11 arranged at the head of said 125 plate. The two outer strings of the unison are desirably formed from a single strand the ends of which are secured each to one of said tuning pins 11, while the other end is looped at 99 through eyes 101, 103 formed in 130

the upstanding leg of said angle 87 and lead obliquely over the adjacent end of the strut 30 where it engages the end of the middle string and firmly binds it within the hole 97. 5 The end of the strut 30 is grooved along the path following by said loop so as to prevent said loop from slipping off of said end. With this arrangement it will be seen that as tension is applied to the strings by the tuning pins the two parts bound by said strings will be firmly held together in anti-rattling relation.

10 To provide for variations in distance between the reenforcing strip 85 and the strut 30 one or more shims or blocks may be inserted at 105 between the angle piece 87 and said strip 85, thus providing means whereby a very accurate or delicate adjustment of the sounding board and string may be effected. 15 Furthermore, these shims or blocks may be utilized to compensate for variations in the spacing between the free ends of the struts and the strip 85 on the sounding board due to the arching of said strip and sounding board.

20 When the struts 30 are rather flexible and subject to rapid vibration there is sometimes danger of shimmering, and to reduce or substantially prevent such shimmering some at least of said struts are ribbed at points intermediate their free and fixed ends as shown at 106, Figs. 5 and 9, these ribs tending to absorb the vibrations and also to stiffen the strut.

25 The said struts 30 are also offset as for example at 107 for a purpose which will now be explained. In this connection it will be obvious that where the base 37 of the strut is supported from the under face 45 of the string plate, as shown in Figs. 2, 3 and 5, the tension of the strings secured to said struts will have a tendency to deflect said struts downwardly toward the sounding board 7 in a manner to counter-balance the forces 30 exerted by the sounding board toward the string, but if the tension of the bass and lower treble strings is sufficient fully or substantially to counteract the pressure of said board the pressure exerted by the individual struts 35 of the upper strings toward said sounding board due to the tendency of the strings 33 or 32, as the case may be, to bend said struts downwardly away from the face 45 of the string plate, this pressure may be greater than that of the board 7 and consequently there will not be a balance of forces at that particular point. Therefore to guard against this over-balance the position of said offset 40 107 may be varied with regard to the face 45 or at least in relation to the strings and the strut between said offset and bass be of such rigid construction that substantially no flexing will result between said points but all flexing of said strut will take place between the point 107 which may be termed the flex-

ing base of the strut and the free end thereof. In other words, the location of said point 107 may be varied with different struts so as to produce an upward movement in the direction of the arrow *a*, Fig. 7, or a downward movement in the direction of the arrow *b*, or said offset may be located at such a point as to neutralize any tendency on the part of the strut due to the tension of the string to be deflected up or down. By careful calculation and experimentation the exact location of said offset 107 may be determined for each individual strut with the result that all up and down forces throughout the board or series of strings may be regulated to substantially counter-balance the forces of the adjacent portion of the board.

25 In cases where the offset of the struts 30 is slight, such for example as shown in Fig. 5, the body of the strut will be above the strings although the stiffening ribs 106 may extend below said strings. Figs. 6 and 7, on the other hand, show a strut that has a much greater offset wherein the point 107 lies below the strings and so also will the body of said strut lie below said strings. In the latter case the side ribs 106^a, which are modifications of the ribs 106 of the form shown in Fig. 5, are called upon to form the entire support for the strings and to resist whatever pressure is exerted by the sounding board at that point, the web of the strut being cut away at 108 between said ribs for a portion of the length of the strut to clear the strings.

30 In Fig. 10 I have illustrated another form of strut 30 adapted to be used in cases where the pressure exerted by the sounding board against the strings is relatively great, requiring a stiffer strut body. Here the strut is offset at 107^a but very little so that the tension of the strings secured to this strut acts to bend the strut downward in the direction of the arrow *c*.

35 It is within the scope and purpose of the invention to employ the same method of offsetting or regulating the lateral deflection of the strut plates 49 and 59 as employed in the individual struts for the upper groups of strings, but in the present example means are provided for reenforcing said struts 49 and 50, said means herein consisting of cushions 109 (see Fig. 4), placed at suitable distances along the edges of said strut plates, each of these cushions being composed of rubber or other resilient material and connected herein by a bolt 111 extending through an opening 113 formed in the shelf 77 or in the shelf 71, as the case may be, thence into screw threaded engagement with the free edge 67 of the auxiliary strut 59. A lock nut 115 may be provided for the upper end of said bolt to engage the upper face of said plate 59 and prevent unintentional loosening of the bolt. A metal washer 117 may be and herein is shown placed against the lower face of the cushion 109,

wherein it is held by a nut 119 secured to the lower end of the bolt 111. By careful adjustment of the nut 113 or the screw 111 the desired resistance to the upward deflection of 5 the strut 59 may be obtained.

All of the struts hereinbefore described have been formed separate from the string plate but it is to be understood that the invention is not limited to that construction 10 but these struts may be made integral with said string plate as illustrated in Figs. 11 and 12.

In this embodiment a strut plate 120 similar to the plates 49 and 59 of Fig. 4 is cast 15 integral with the marginal portion 121 of the shelf 122, which latter forms an integral part of the string plate 3.

Strings may be secured in the usual manner to the edge 123 of said strut plate and a 20 reenforcing cushion 124 may also be used to function as do the cushions 109 in Fig. 4.

In Figs. 11 and 12 a somewhat modified form of connection between the cushion 124 and the strut 120 is shown which includes a 25 bridge plate 125 which bridges the gap 17^a of the string plate and rests at opposite ends respectively against the under side of the strut 120 and said cushion 124. The end 127 of said bridge 125 is positioned within 30 a depression 128 to prevent movement thereof. A bolt 126 adjustably secures said bridge plate 125 to the free edge 123 of the strut 120, thus providing adjustable auxiliary supporting means therefor.

Although I have disclosed and discussed 35 in detail one full and complete embodiment of my invention, it is to be understood that the invention is not limited thereto.

Claims:

1. In a stringed instrument, at least one 40 string, relatively yielding hitching means for said string tending to yield, when said string is under tension, in one direction laterally to said string, and a sounding board associated with said string, means to maintain said 45 sounding board under stress tending to exert pressure laterally to said string and in opposition to the forces exerted by said string whereby a substantial balance of forces may be maintained between said string and said 50 sounding board.

2. In a stringed instrument, a string supporting plate, strings stretched across said plate, resilient supporting means interposed 55 between at least one end of the strings and said plate tending to yield laterally to said string in one direction under tension of said string, a sounding board associated with said strings and means including said plate to exert pressure on said 60 sounding board laterally with respect to said strings in opposition to the pressure of said string whereby a substantial balance of forces between said string supporting means

and said sounding board will be established. 65

3. In a stringed instrument, a string supporting plate, strings stretched across said plate, resilient supporting means interposed between at least one end of the strings and said plate tending to yield perpendicularly 70 to and away from the face of said plate under the tension of said strings, a sounding board associated with said strings and means to maintain said sounding board under stress to exert pressure thereon substantially equal and in opposition to the said perpendicular yielding pressure on said strings, whereby a substantial balance of forces between those exerted by said strings and said sounding board will be established. 75

4. In a stringed instrument, a string supporting plate, strings stretched across said plate, means for securing said strings to said plate including relatively resilient cantilevers which have a tendency to yield perpendicularly to the plane of said strings away from said plate, a sounding board arranged adjacent to said plate, means to hold said sounding board under tension to exert pressure in opposition to the direction of yield of said cantilevers, and bridge means carried by said sounding board and operatively connected with said strings. 85

5. In a stringed instrument, a string supporting plate, strings stretched across said plate, means for securing said strings to said plate including a resilient cantilever having one end fixed to said plate intermediate the ends of its string, said cantilever tending yieldably to resist lateral deflections of said string, a sounding board operatively connected with said string and means to hold said sounding board tensioned to exert pressure laterally of said strings and in opposition to the resistance to lateral deflection offered by said cantilevers. 100

6. In a stringed instrument, in combination, a string supporting plate, strings stretched across said plate, means for securing said strings to said plate including a resilient strut rigidly secured to said plate intermediate the ends of the string, and means formed intermediate the ends of said strut tending to prevent shimmering of said strut during vibrations of its string. 110

7. In a stringed instrument, in combination, a string supporting plate, strings stretched across said plate, means for securing said strings to said plate including a resilient strut rigidly secured to said plate intermediate the ends of the string, said strut having a deflected intermediate portion tending to prevent shimmering of said strut during the vibrations of the string attached thereto. 120

8. In a stringed instrument, in combination, a string supporting plate, strings stretched across said plate, means for securing

ing said strings to said plate including resilient struts fixed to said plate at points intermediate the ends of their respective strings, a sounding board, a bridge secured 5 to said sounding board, and an auxiliary bridge interposed between the free end of each of said struts and said bridge.

9. In a stringed instrument, in combination, a string plate, strings stretched across 10 said plate, means to secure said strings to said plate including resilient struts rigidly secured to said plate at points intermediate the ends of the strings, said struts tending to resist deflection of said strings in a direction 15 perpendicular to the plane of said strings, a sounding board tensioned to exert pressure upon said strings in a perpendicular direction relative to said plane and to balance the resistive forces exerted upon said strings by 20 said struts, and bridge means interposed between the free ends of said struts and said sounding board.

10. In a stringed instrument, in combination, a string plate, strings stretched across 23 said plate, means to secure said strings to said plate including resilient struts rigidly secured to said plate at points intermediate the ends of the strings, said struts tending to resist deflection of said strings in a direction 28 perpendicular to the plane of said strings, a sounding board, means to cause said sounding board to exert pressure upon said strings in a perpendicular direction relative to said 33 plane and to balance the resistive forces exerted upon said strings by said struts, and bridge means secured to said sounding board and held by said forces in constant engagement with said struts.

11. In a stringed instrument, in combination, a string plate, strings stretched across 40 said plate, means to secure said strings to said plate including resilient struts rigidly secured to said plate at points intermediate the ends of the strings, said struts tending to resist deflection of said strings in a direction 45 substantially perpendicular to the plane of said strings, a sounding board, means to cause said sounding board, to exert pressure upon said string in a substantially perpendicular 50 direction relative to said plane and to substantially balance the resistive forces exerted upon said strings by said struts, a wooden bridge secured to said sounding board and a metallic auxiliary bridge member interposed between 55 said wooden bridge and said strut and held in constant engagement with said strut by one at least of said strings.

12. In a stringed instrument, a string supporting plate, strings stretched across said 60 plate, a laterally resilient supporting strut for at least one end of each of said strings, means rigidly to secure said struts to the face of said plate adjacent to said strings, and a sounding board, means to cause said sounding 65 board to exert pressure upon said strings

in opposition to the normal lateral yielding tendency of said struts substantially to balance said lateral yielding tendency.

13. In a stringed instrument, in combination, a string supporting plate, strings 70 stretched across said plate, means for securing said strings to said plate including a resilient strut rigidly secured to said plate, a sounding board, a bridge connecting said strut with said sounding board and means to prevent rattling between said bridge and strut.

14. In a stringed instrument, in combination, a string supporting plate, strings 80 stretched across said plate, means for securing said strings to said plate including a resilient strut rigidly secured to said plate, a sounding board, a bridge connecting said strut with said sounding board and means to prevent rattling between said bridge and 85 strut, including portions of a string supported by said strut.

15. In a stringed instrument, in combination, a string supporting plate, strings 90 stretched across said plate, means for securing said strings to said plate including a resilient strut rigidly secured to said plate, a sounding board, a bridge connecting said strut with said sounding board and means to prevent rattling between said bridge and 95 strut, including portions of the string or strings supported by said strut interlaced with said strut and said bridge.

16. In a stringed instrument, in combination, a string supporting plate having an 100 opening formed therein substantially following a portion of the hitch line of said plate, integral struts bridging said opening at selected intervals and separable struts bridging said opening at points intermediate said integral struts.

17. In a stringed instrument, in combination, a string supporting plate having an 110 opening formed therein substantially following a portion of the hitch line of said plate, integral struts bridging said opening at selected intervals and separable reinforcing struts bridging said opening at points intermediate said integral struts.

18. In a stringed instrument, in combination, a string supporting plate having an 115 opening formed therein substantially following a portion of the hitch line of said plate, integral struts bridging said opening at selected intervals and separable struts bridging 120 said opening and reinforcing said string plate between said integral struts.

19. In a stringed instrument, in combination, a plate, a sounding board, means to maintain said sounding board under stress, a 125 series of strings stretched across said plate, and resilient supporting means for the ends of said strings arranged to maintain a condition of poise between said strings and said sounding board by effecting a substantial bal- 130

- alance between the string tension and the pressure of said sounding board thereby promoting increased harmonic activity through the scale.
5. 20. In a piano, in combination, a plate, a stressed sounding board, a series of strings stretched across said plate, said plate including resilient string supporting means arranged to maintain a condition of poise by 10 effecting a substantial counteraction of the pressures of the string tension and that of said sounding board. 70
15. 21. In a piano, in combination, a plate, a stressed sounding board, a series of strings stretched across said plate, said plate including integral resilient string supporting means arranged to maintain a condition of poise by effecting a substantial counteraction 15 of the pressures of the string tension and 20 that of said sounding board. 80
25. 22. In a piano, in combination, a plate, a sounding board, a series of strings stretched across said plate, said plate embodying resilient string supporting means to maintain a condition of poise between said strings and said sounding board and adapted to effect a substantially equal counteraction of forces 30 acting between the said sounding board and said strings whereby an increased harmonic 35 activity will be promoted through the scale. 90
35. 23. In a piano, in combination, a plate, a series of strings stretched across said plate, a sounding board arranged to exert pressure laterally to said strings, resilient means carried by said plate and proportioned relative 40 to the string mass and velocity of vibration thereof to effect a substantial balance of the opposing forces acting between said strings and said sounding board thereby to promote a harmonic activity through the scale. 100
45. 24. In a piano, in combination, a string plate, a series of strings stretched across said plate, a sounding board arranged to exert pressure laterally toward said strings, a bridge secured in stressed relation to said board, and resilient means on said string plate proportioned relative to the string mass and velocity of vibration to effect a substantial balance of the pressure of said board and 50 said bridge upon said strings thereby to promote a harmonic activity through the scale. 105
55. 25. In a piano, in combination, with a string plate and a stressed sounding board, of bass and treble strings stretched across said plate, laterally resilient means interposed between the tails of said strings and said plate to provide a flexible hitch line, the laterally resilient means for the lower strings of the series being relatively stiff to maintain the 60 pressure of said sounding board in substantial balance. 110
65. 26. In a piano, a string plate, a series of strings stretched adjacent to said plate, a stressed sounding board, laterally resilient, longitudinally rigid supporting means for 115
- said strings, bridge means interposed between said strings and said sounding board, the supporting means for the lower strings being relatively stiffer than those of the upper strings to carry the larger amount of board pressure. 120
27. In a piano, a string plate, a series of strings stretched adjacent to said plate, means to maintain said sounding board under stress, laterally resilient, longitudinally rigid supporting means for said strings, bridge means interposed between said strings and said sounding board, the laterally resilient, supporting means for the lower strings being adapted to substantially balance the opposing pressure of said sounding board and providing a relatively greater degree of freedom 125 for the supporting means for the upper strings. 130
28. In a stringed instrument, in combination, a string plate, a series of strings stretched across said plate, a sounding board under stress to exert pressure laterally toward said strings, laterally resilient string supporting means carried by said string plate adapted to resist the pressure exerted by said sounding board toward said strings and means to reinforce said laterally resilient means. 135
29. In a stringed instrument, in combination, a string plate, a series of strings stretched across said plate, a sounding board, means to cause said sounding board to exert pressure laterally toward said strings, laterally resilient string supporting means carried by said string plate adapted to resist the pressure 140 exerted by said sounding board toward said strings and cushioning means to effect a balance between the opposing forces exerted by said sounding board and said string supporting means. 145
30. In a stringed instrument, in combination, a string supporting plate, strings stretched across said plate, means for securing said strings in said plate including a resilient strut rigidly secured to said plate intermediate the ends of the string, and stiffening means formed intermediate the ends of said strut tending to prevent shimmering of said strut during vibrations of its string. 150
31. In a stringed instrument, in combination, a string plate, a series of strings stretched across said plate, a sounding board under stress to exert pressure laterally toward said strings, laterally resilient string supporting means carried by said string plate 155 adapted to resist the pressure exerted by said sounding board toward said strings and resilient means interposed between a relatively fixed portion of the instrument and said laterally resilient string supporting means to reinforce said resilient means. 160
32. In a stringed instrument, a string plate, strings stretched across one face of said plate, and laterally yielding string supporting means fixed upon the aforesaid face of said 165

plate, and having an offset portion extending from said plate a predetermined distance beyond the string supported thereby, said offset forming the point about which some at 5 least of the flexing of said string supporting means takes place.

33. In a stringed instrument, in combination, a string plate, a series of strings stretched across said plate, a stressed sounding board 10 adjacent the face of said plate across which said strings are stretched and arranged to exert pressure toward said strings, laterally resilient longitudinally rigid supporting means for the ends of said strings, and bridge

means between said strings and said sounding board, some at least of said supporting means each having an offset formed in its length constituting the flexing base of said supporting means and positioned relatively to its string to provide the degree of resistance 20 desired to oppose the pressure exerted by the sounding board at that point, whereby a substantial balance of pressures between said strings and said sounding board will be obtained. 25

In testimony whereof, I have signed my name to this specification.

EDWARD W. POWERS.

CERTIFICATE OF CORRECTION.

Patent No. 1,703,169.

Granted February 26, 1929, to

EDWARD W. POWERS.

It is hereby certified that error appears in the printed specification of the above numbered patent requiring correction as follows: Page 1, line 75, for the word "springing" read "stringing"; page 7, line 109, claim 30, for the word "in" read "to"; and that the said Letters Patent should be read with these corrections therein that the same may conform to the record of the case in the Patent Office.

Signed and sealed this 26th day of March, A. D. 1929.

(Seal)

**M. J. Moore,
Acting Commissioner of Patents.**
